(57) **CLAIM**

The ornamental design for a sleeve for a glass vessel, as shown and described.

DESCRIPTION

FIG. 1 is a perspective view of a sleeve for a glass vessel showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The sleeve material is an opaque or translucent, pliable polymer material. The broken line elements in all views are for illustrative and environmental purposes only and form no part of the claimed design.
